UNITED STATES PATENT OFFICE

WILLIAM A. ERVIN, OF OAKLAND, CALIFORNIA

HINGE

Application filed November 27, 1929. Serial No. 410,099.

The invention is for a compound hinge, and has special reference to a hinge to be used on doors cooperating with openings of irregular or warped shape, such as the doors 5 of an automobile.

The main object of the invention is to provide a type of concealed hinge which will compensate for varying required movements of the upper and lower sections of the door, 10 for the purpose of retaining the top and bottom edges of the door in substantially horizontal planes at all degrees of opening, also providing means whereby said hinge prevents excess angular opening of said door, and, 15 reverse buckling of said hinge, thus, also, replacing the typical check strap.

Other objects of the invention will become apparent as the description is set forth, and from the appended claims.

20 It is to be noted that the invention is not limited to the exact construction indicated in the drawing, and that such changes in construction as are consistent with the description and appended claims will not detract 25 from the spirit or scope of the invention or sacrifice any of the advantages thereof.

Similar reference characters are used to designate similar parts in the accompanying drawing throughout the several views.

30 Referring to the drawing:

Fig. 1 illustrates the hinge as applied to an automobile door and showing the door in open position;

Fig. 2 illustrates the hinge in closed position;

Fig. 3 is a side elevation of the closed hinge.

Fig. 4 illustrates a top plan view of the upper hinge in open position as presented in 40 Fig. 1;

Fig. 5 is a general view of the hinge in open position.

Reference character 1 designates the body of an automobile or frame for a door, said 45 door being designated by the numeral 2. The upper and lower hinges are designated as an entirety respectively by numerals 3 and 4.

The hinge, Fig. 5, comprises a pair of main hinge plates 5 and 6 provided with holes 7 50 for attachment respectively to the door and

frame, and have at their upper ends, hingedly connected by pins 8, a pair of hinged cooperating members 9 and 10, the axis of hinge joint 11 between members 9 and 10 being in angular relation to hinge joints 8. Hinge 55 joints 8 are outwardly disposed and hinge joint 11 inwardly disposed as indicated in Fig. 2, thus permitting contact of faces 5, 6, 9 and 10 upon complete closure of said hinge.

Equalizers 12 and 13 comprise continuations of plates 9 and 10 respectively beyond the hinge eyes 14 and 15, the ends of said continuations being arcuately formed. Equalizers 12 and 13 are so disposed and formed as to bear against the surface 17 of 65 the mortise 16 when the door is closed, as also during the initial opening and final closing movements of the door 2, thereby equalizing the action of plates 5, 6, 9 and 10 during initial opening and final closing movement, 70 and preventing rattling of said hinge when said door is closed.

During the initial opening and final closing movements, the weight of the door would have a tendency to keep plate 10 in contact 75 with the door, thereby producing a sag. Equalizer 13 swinging in opposition prevents this condition by forcing joint 11 away from contact with the door. After a slight angular divergence of plates 5 and 6 is attained, 80 sag is prevented by the angularity of the complementary joints, producing a twisting action to the plates 5 and 6. Therefore, sag is further prevented by the resistance of the mounted plates 5 and 6 and their attaching 85 means to twisting stresses. Extensions 12 and 13 also prevent reverse buckling and consequent locking of the hinge in open position by preventing interposition of hinge joint 11 in the same horizontal plane with the two 90 hinge joints 8.

The door and cooperating support may be mortised to receive the hinge as indicated at 16 and 17, in which event complete closure will be obtained between door and frame, the 95 hinge being thereby concealed.

The invention as illustrated is a preferred embodiment of the device.

I claim:

1. In combination, a hinge, comprising a 100

- pair of attachable body plates, hingedly connected to an angular hinge, said angular hinge being provided with equalizers, said equalizers consisting of inward extensions of the angular hinge plates adapted to provide uniform action of the hinge members during the initial opening and final closing movement of a door by cooperation with the door frame, and to prevent rattling of said hinge members when said door is closed.
10. 2. In combination, a pair of body plates adapted to be attached respectively to a door and its support, said body plates being respectively hingedly connected to the divergent edge of the leaves of a complementary angular hinge, said complementary angular hinge being provided with means to cooperate with a door and its support for the purpose of equalizing the action of said leaves during initial opening and final closing movement of said door and to prevent rattling of said hinge when said door is in closed position, and cooperating with said leaves to prevent excess angular divergence of said body plates.
15. 3. In combination, a pair of rectangular mounting plates hingedly connected to a pair of hinge plates angularly connected relative to the connection with said mounting plates, and integral extensions beyond the angular connection, the ends of said extensions being arcuately formed and adapted to cooperate with the door and door frame during initial opening and final closing movements of the door.
20. 35. 4. In combination, a pair of rectangular plates hingedly connected to a pair of hinge plates angularly connected, said hinge plates being provided with means adapted to engage the supporting surfaces in opposition during initial opening and final closing movements of said hinge.
40. In testimony whereof I have affixed my signature.

WILLIAM A. ERVIN.
